UNITED STATES PATENT OFFICE.

THOMAS W. MILLER, OF ASHLAND, OHIO, ASSIGNOR TO THE FAULTLESS RUBBER CO.,
OF ASHLAND, OHIO, A CORPORATION OF OHIO.

BATHING-CAP.

1,215,311.

Specification of Letters Patent.

Patented Feb. 6, 1917.

Application filed November 17, 1916. Serial No. 131,892.

To all whom it may concern:

Be it known that I, THOMAS W. MILLER, a citizen of the United States, residing at Ashland, in the county of Ashland and 5 State of Ohio, have invented certain new and useful Improvements in Bathing-Caps, of which the following is a specification.

My invention relates to bathing caps, and has for its main object to provide an improved construction of the same, whereby said cap, when placed upon the head of the wearer, will form a water-tight closure at its edge, and at the same time will not be open to the objection heretofore made to 15 water-tight caps that they bind the head of the wearer to an uncomfortable degree.

A further object of my invention is to provide the body of the cap with a pad fastened thereto, preferably upon its inner surface, said pad being composed of sponge rubber and affording a protection to the head of the wearer in the event that an object is struck in diving.

These objects I accomplish in the manner 25 and by the means hereinafter described and claimed, reference being had to the accompanying drawing, in which:—

Figure 1 is a perspective view of my improved bathing cap.

30 Fig. 2 is an enlarged detail sectional view of a portion of the cap, taken through the band of the same.

Fig. 3 is a view similar to Fig. 1 with the upper portion of the cap shown in section.

Similar numerals of reference denote corresponding parts in the several views.

In the said drawing, the reference numeral 1 denotes the body of the cap, which, 40 as usual, is made of thin rubber, or any other material impervious to water, to afford a water-tight covering. At approximately its rim or edge, the cap is provided with a roll 2 of rubber sponge, the same forming the 45 cap band.

By means of said roll, I provide a band

for the cap which is capable of stretching or elongation in its application to the head of the wearer, and yet will afford a thoroughly water-tight but extremely soft and 50 comfortable compressing element, which in no way will present any objectionable features to the wearer.

While I have illustrated the edge of the cap as folded around the roll 2 and cemented thereto, as best seen in Fig. 2, I 55 wish it to be understood that I do not limit myself to any such construction, as the cap 1 may be united to said roll 2 in any other desired manner.

In Fig. 3 I have shown a pad 3, of sponge rubber, disposed in the top of the cap, and preferably cemented thereto, or secured in any other suitable manner, the same affording a protection to the head when the wearer 65 of the cap is diving and in the event that the head strikes an object. It will be understood, however, that this pad may be omitted if desired, as it in no way affects the main function of the cap, which is to provide a thoroughly water-tight but comfortable head covering for bathing purposes.

Having thus described my invention, what I claim as new and desire to secure by Letters Patent, is:—

1. A bathing cap, embodying a flexible water-proof body, and a band of sponge rubber.

2. A bathing cap, embodying a flexible water-proof body, and an unbroken band 80 of sponge rubber, around which the edge of the cap is folded, said edge being cemented thereto and said edge and roll constituting the cap rim.

3. A bathing cap, embodying a flexible 85 water-proof body, and a pad of sponge rubber fixed to the interior central portion of said body.

In testimony whereof, I hereunto set my hand this ninth day of November, 1916.

THOMAS W. MILLER.
